Primary Examiner — Jack Reickel*Assistant Examiner* — Bobby W Jones, II(57) **CLAIM**

The ornamental design for an air cooler as shown and described.

DESCRIPTION

FIG. 1 is a front perspective view of an air cooler showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and

FIG. 8 is a rear perspective view thereof;

FIG. 9 is an enlarged detail view taken from portion 9 of FIG. 1;

FIG. 10 is an enlarged detail view taken from portion 10 of FIG. 5; and,

FIG. 11 is an enlarged detail view taken from portion 11 of FIG. 8.

The long-dash broken lines encircling portions of the air cooler in FIGS. 1, 5 and 8 and illustrated in enlarged views in FIGS. 9-11 form no part of the claimed design.

1 Claim, 11 Drawing Sheets(56)
